UNITED STATES PATENT OFFICE.

STEPHEN N. CHAPMAN, OF MOODUS, CONNECTICUT.

IMPROVEMENT IN SHINGLING-BRACKETS.

Specification forming part of Letters Patent No. 179,522, dated July 4, 1876; application filed February 5, 1876.

To all whom it may concern:

Be it known that I, STEPHEN N. CHAPMAN, of Moodus, in the county of Middlesex and State of Connecticut, have invented a new and Improved Roof-Bracket Stay, of which the following is a specification:

In the accompanying drawing, Figure 1 represents a side view of my improved bracket-stay as applied to the shingles of a roof, and Fig. 2 is a top view of the same.

Similar letters of reference indicate corresponding parts.

My invention relates to an improved bracket clamp or stay for the purpose of putting up stagings on shingled roofs; and it consists of a clasp-piece that is slipped on the butt of the shingle, and fastened by a supporting-arm with an eccentric spur locking thereto. The bent-up end of the supporting-arm rests on the roof and supports the staging.

In the drawing, A represents the clasp, made of V-shaped spring-steel, of which the lower tapering end is longer than the upper, and placed below the butt of the shingle. To the upper shorter end of the clasp is hinged the supporting-arm B, that is provided at the pivot or hinge end of the clasp with a projecting spur, C, which assumes, when the arm

B is thrown up, a position in the recess a of the upper clasp end, and which enters or "bites" into the top part of the shingle when the supporting-arm B is thrown down to rest with its outer angular part on the butt of the next course of shingles.

The bent-up outer end of arm B forms the support or stay for the staging, which is, by the use of a number of brackets, strongly and securely supported, while admitting the ready putting up and taking off of the staging.

When the supporting-arm is swung up the spur releases the shingle, and the bracket-stay may be readily slipped out, saving thereby time and expense in erecting the staging, and dispensing with the nailing through or otherwise injuring the roof.

Having thus described my invention, I claim as new and desire to secure by Letters Patent—

A spring-clamp, A, combined with a pivoted spur-arm, B C, having rear angle-arm, to form a stay for the staging, as shown and described.

STEPHEN N. CHAPMAN.
